FLUTED DELIVERY ROLL

John T. Ahearn, Lowell, Mass.

Application October 3, 1933, Serial No. 691,939

4 Claims. (Cl. 19—141)

This invention relates to textile drawing rolls particularly of the type known as fluted rolls which are used in spinning frames, twisting frames, drawing frames and other similar machines.

Some of these frames are of great width and the drawing roll may be anywhere from five or ten to forty feet in length. Each complete roll or roll assembly is formed with bosses fluted longitudinally and between these bosses there are generally necks some of which may be bearings or there may be at suitable intervals other bearing parts which may be of greater or less diameter than the necks.

Such textile drawing rolls are frequently made of hard steel rods and in lengths of five, ten or twenty feet which have been turned down and the flutes machined. The parts must be hardened and the machining must be very accurate and is very expensive and if any part becomes dented or broken a large section must be removed while the frame is stopped and the repair is slow and expensive.

To avoid the use of very long, integral rolls various coupling devices have been used which involve the cutting of internal and external screw threads or square holes at the end of a cylindrical hole all of which are very expensive and very difficult to cut accurately.

The purpose of this invention is to provide a textile drawing roll made up of sections which are firmly coupled together in such a manner as to make a roll of any desired length and one in which the sections can be taken apart only by the application of heat. For this purpose, I use relatively short roll sections each having fluted bosses on the outside separated by suitable necks, the adjoining sections being coupled together by a special type of coupling which preferably consists of a hard metal rod soldered into the adjoining ends of adjoining sections.

I also provide a special coupling by which adjoining rolls each made up of several sections can be connected and disconnected without the use of heat.

A roll of my construction is cheap, light and at the same time is well balanced and can readily be taken apart for repairs.

In the drawing, Fig. 1 is an elevation partly in section and broken so as to show a plurality of roll sections connected together.

Fig. 2 is a view similar to Fig. 1 showing a modification of the coupling.

Fig. 3 shows another modification of the construction.

Fig. 4 is an isometric view of a stop member and Fig. 5 is an isometric view of a modified form of stop member.

Fig. 6 is an isometric view showing one form of coupling member.

Fig. 7 is an isometric view of a modification of the coupling member.

In the drawing, Fig. 1 shows how several sections such as C, F and B are united to form a larger section or a whole roll. Each section is of 10 tubular form with an axial passage 24, 34, or 44 which extends through it and on the outside is provided with fluted bosses 21, 31 or 41 separated by necks 22, 32 or 42 of less diameter than the fluted bosses.

At each end of each section is an axial recess such as 23, 33, 133 or 43 which is of greater diameter than its adjoining passage 24, 34 or 44. These recesses are preferably and are shown as being of cylindrical form and are practically counter-bores at each end of each tubular section. In this way, there is formed between each passage and at the end of each recess an internal shoulder such as 25, 35, 135 or 145 and against each of these shoulders, I first place a stop disk 15 20 25 preferably of metal such as H, H, H, H so that it rests against a shoulder and blocks up the axial passage.

To connect any two sections such as C, F and B, I use cylindrical hard metal rods as coupling members which are indicated by G, G, G, G, each member G being of a size to slip easily into a recess such as 23, 33, 133 or 143 until it rests against a disk H.

In assembling the whole roll, after the disks H are put in place, a sufficient amount of solder S, preferably of low fusibility, is poured into the appropriate recess and then a coupling G is pushed into place so that when the solder hardens, it is firmly and accurately held in such a way that it will not separate from the tubular section.

By using a solder of low fusibility in connection with any well known type of electric heater, a roll section can be taken apart in the mill 45 without danger of fire or, of course, a blow torch or other similar heating medium can be used.

By using tubes for roll sections, with an axial passage, the weight and the cost of metal is reduced while at the same time by counterboring or forming at each end a concentric cylindrical axial recess of greater diameter than the axial passage of the tube, an annular shoulder is formed which permits the stop disc to be inserted and to limit the distance in which the coupling 50 55

member will go. While this stop disc prevents the solder from running into the axial passage of the tube, it permits the air to go through and the result is that the solder is evenly distributed between the coupling member and the counter-bore. If such stop discs were not used, the solder would run into the axial passage and be not only useless, but would unbalance the whole roll. A solder of such low fusibility that it will melt at the boiling point of water can be used and there is, therefore, no injury to the metal either when assembling or disassembling the parts.

However, as a matter of convenience in connecting some of the sections so that what might be called a major section, which includes several of the small sections, can be instantly taken out without the use of heat, I may provide at intervals a modification of my coupling members such as shown in Figs. 2, 3, 6 and 7.

In Figs. 2 and 3 instead of a single integral coupling such as G between two sections, I use a compound coupling including two cylindrical coupling members such as K and L each of which enters a recess in the end of adjoining sections and rests against a disk therein. One of such coupling members such as K projects from one end and the other such as L terminates inside its recess. The outer ends of each of said coupling members K and L are cut straight across, as at 1 and 3, leaving stubs 2 and 4 which, when the adjoining couplings are fitted together, entirely fill the recess and make a perfect joint which will hold the parts together without rattling or slipping.

As shown in Fig. 7, instead of cutting the ends of these adjoining coupling members straight across forming half circles, I can use a mortise construction in which the cuts 5 and 6 leave a tenon at 7 which enters a mortise groove 8 between the two ends 9 and 10 of an adjoining coupling which terminates inside its recess.

Couplings such as shown and described in Figs. 2, 3, 6 and 7 can obviously be used between any two of the minor sections such as C, F and B and as they do not require any careful machining or screw cutting, they are much less expensive and at the same time are as accurate or more accurate than other constructions.

As shown in Fig. 3, a type of coupling such as shown at K and L, with either cutting shown in Figs. 6 or 7, can be used with roll sections such as R and T made of solid metal with recesses such as 53 and 63 into which they are soldered.

Instead of disk stops such as H, I may use stops of mushroom shape such as shown at V in Fig. 5 having a neck 70 which enters a passage and a cap 71 which rests against a shoulder.

I claim:

1. In a textile drawing roll, roll sections each having an outside fluted part and being of tubular form with an axial passage which extends through it and having at each end a cylindrical axial recess of greater diameter than said passage whereby an internal shoulder is formed; metal stop disks each of which rests against a shoulder; and two cylindrical coupling members, each of which enters a recess, rests against a stop disk and is soldered in place, one of said coupling members projecting from one end and the other terminating inside its recess, the outer ends of said coupling members being cut straight across in such manner that when the ends of adjoining couplings are fitted together, they fill the recess.

2. In a textile drawing roll, roll sections each having an outside fluted part and being of tubular form with an axial passage which extends through it and having at each end a concentric cylindrical axial recess of greater diameter than said passage whereby an internal shoulder is formed; metal stop disks each of which rests against a shoulder; and a cylindrical coupling member which enters a recess, rests against a stop disk and is soldered in place, the stop disks acting to prevent the solder from running into the axial passage while permitting the escape of air thus facilitating the even distribution of the solder between the coupling members and the walls of the recesses.

3. In a textile drawing roll, roll sections each having an outside fluted part and an axial passage which extends through it and having at each end an axial recess of greater diameter than and concentric with said passage whereby an internal shoulder is formed; stop disks each of which rests against a shoulder; and a coupling member which enters a recess, rests against a stop disk and is soldered in place, the stop disks acting to prevent the solder from running into the axial passage while permitting the escape of air thus facilitating the even distribution of the solder between the coupling members and the walls of the recesses.

4. In a textile drawing roll, a roll section having a passage which extends through it and also having at one end an axial recess; a stop member interposed between said passage and recess; and a coupling member which enters said recess, rests against said stop member and is soldered in place, said stop member acting to prevent the solder from running into the passage while permitting the escape of air thus facilitating the even distribution of the solder between the coupling member and the wall of the recess.

JOHN T. AHEARN.
